UNITED STATES PATENT OFFICE

WALTER DOUGLAS LA MONT, OF LARCHMONT, NEW YORK, ASSIGNOR TO LA MONT CORPORATION, A CORPORATION OF NEW YORK

STEAM GENERATOR

Application filed June 11, 1926. Serial No. 115,169.

This invention relates to the generation of steam or other vapors and has for its object the generation of steam or vapor under different pressures by generators which have a common series or series parallel water or liquid circulation. Other and further objects and advantages of the invention will appear from the detailed description which follows.

10 In my co-pending application, Serial No. 79,096, filed January 4, 1926, patented July 21, 1931, Patent No. 1,815,439 I have described steam generator installations in which generators of the film tube type which have been described in my prior Patent No. 1,545,668, dated July 14, 1925, and in my co-pending application, Serial No. 32,064, filed May 22, 1925, are used in combination with boilers of conventional designs to increase the efficiency of these installations and to improve the operation and particularly the circulation of the conventional type boilers by connecting the positive circulation of the film tube generators in series, parallel, or series parallel with the water mass of or the convection circulation in the conventional type boilers, thereby not only increasing the overall efficiency of the installation as a whole by adding highly efficient heat transfer surface 20 in the form of film tubes which permit operation with a much lower stack temperature than has hitherto been practicable but rendering the conventional type boilers themselves more efficient as steam generators. The present invention is in part a continuation of my above referred to application, Serial No. 79,096, and embodies and includes improvements in the general type of installation therein described, as well as other features of novelty.

According to the present invention, two or more generators are provided with at least part of their circulation in common and the installation is arranged so that steam or other vapors of different pressures can be generated from the different generators without disturbing the common circulation of water or other liquid. One or more of the generators may advantageously have positive circulation. When one or more positively

circulated generators are combined according to the present invention, particularly where a series or series parallel water flow is provided, the circulation in all the generators is improved and this type of arrangement constitutes the preferred broad embodiment of the present invention.

In the ensuing descriptions, I will refer to steam generators and to the generation of steam, but it should be understood that the present invention is equally applicable to the generation of vapors from any liquid or any mixtures of liquids and that, therefore, the features which are described in connection with the generation of steam are in the main equally applicable to the generation of other vapors.

As the generator having positive circulation, I prefer to use a film tube generator as described in my above referred to prior applications and patent. In its broadest aspect, however, the present invention is not limited to combined installations in which one or more La Mont film tube generators are utilized, and, on the contrary, any generator with positive circulation may be substituted for the La Mont film tube generator with a corresponding decrease in heat transfer efficiency. The film tube generator, however, presents so many advantages with regard to ease of construction and installation, heat transfer efficiency and the like, that it constitutes the preferred positive circulation generator in installations according to the present invention and while the broad concept of the present invention is not limited to combinations utilizing this type of generator, in its more specific aspects the combination with one or more common types of convection circulated boilers, operating to generate steam at different pressures, is an important feature of the preferred embodiment of the present invention.

Under the term "positive circulation" I include pumps of all kinds and other devices which positively and definitely circulate water. I do not, in this application, claim the use of generators in which a geyser action is effected in the generating tubes, this forming part of the subject-matter of my co-

pending application, Serial No. 116,305, filed June 16, 1926 patented Oct. 13, 1931, Patent No. 1,827,244.

When two generators are to be operated at different pressures and a series or series parallel circulation of water through the generators is to be provided, it is necessary to provide two pressure transformers, one to reduce the pressure of water fed from the high pressure generator to the low pressure generator and one to increase the pressure of the water fed from the low pressure generator into the high pressure generator. This latter pressure transformer must, of necessity, be a positive circulation means; that is to say, a means which adds energy to the medium circulated. This means is usually one or more pumps, in series or in parallel. The pressure transformer for reducing feed pressure from the high pressure generator to the low pressure generator may be a simple throttling device in which pressure reduction is effected by the speed of flow of the water or energy absorbing means such as water turbines and the like may be used in order to bring about the desired equalization of pressure. In many cases where the high pressure generator is much smaller in capacity than the low pressure generator, a throttle valve may be unnecessary as a pipe connection of small size may exert sufficient throttling action and minor variations will be compensated for by the large volume of water in the low pressure generator. Where a throttle valve is omitted it should be understood that the feed tube itself is acting as a throttle or pressure transformer.

Connection between the two generators may be entirely in series, that is to say, all of the circulating water is circulated in series through both generators or a series parallel arrangement can be provided whereby all of the water in one generator is circulated in series through the other generator but this water does not include the whole of the circulating water in this latter generator. In some cases, a complete series circulation is not necessary or desired and either the high or low pressure boiler may be caused to feed water into the other without any return. Thus, the low pressure generator may act to heat the feed water for the high pressure generator in addition to its function as a steam generator and conversely, of course, the high pressure generator may feed into the low pressure generator through a suitable throttle valve.

The heating gas flow through the generators can be in various forms. Thus, for example, the gases may circulate first through one generator and then through a second and may strike either the high pressure generator first or the low pressure generator first. Parallel gas flow through the two generators is also possible and frequently desirable and

various combinations of series and parallel flows can be used and may be desirable under certain structural or operating conditions. Separately fire generators may also be used, and, as a matter of fact, they can be considered really as a special case of pure parallel gas flow since it is thermally, although not structurally, immaterial whether two gases are generated by separate flames or whether a single flame is used and the gases are divided into two parts. Accordingly, hereafter the expression "parallel flow of heating gases" will be used to include separate firing of the generators as well as utilizing part of the gas from a single fire for one generator and part for the other.

While the invention is not limited to any particular heating gas flow or to any particular combination, for certain purposes a series flow of heating gases possesses notable economic and thermodynamic advantages. Thus, for example, a film tube generator can be easily and simply installed in the stack of an ordinary generator furnace which position is particularly advantageous as it permits the use of very long tubes with a corresponding high efficiency in the film tube generator. Owing to the fact that the film tube generator has a very high heat transfer capacity, it is easily possible in most cases to produce a zero heat head or a heat head actually less than zero. That is to say, the stack gases, on leaving the film tube generator, may be reduced to a temperature equal to that of the steam generated or even less, since the water circulation in a film tube generator is from top to bottom and is, therefore, counter to the gas flow, making it possible in some favorable installations to bring down stack temperatures to a point intermediate between the temperature of the steam generated in the film tube generator and the temperature of the water introduced into the top of the film tubes. Such an arrangement is structurally and thermally very efficient and advantageous and is included as a specific feature of novelty of the present invention in some of its preferred embodiments.

The film tube generator and analogous positive circulation generators may be used as the high pressure or low pressure members. When used as the low pressure member in the coldest heat zones with a series heating gas flow, the greatest thermal efficiency can be achieved and this arrangement is peculiarly suited to the structural features of the film tube generator which requires for greatest efficiency long, small tubes, readily fitting into the stack of boiler furnaces. On the other hand, the small tubes and high heat transfer capacity of film tube generators make them peculiarly suitable for generating high pressure steam, particularly where they are placed in the hottest zone of the furnace. When so placed, the thermal efficiency of the

whole installation is decreased, if the generator in the low temperature zones is of the convection type. However, the structural and operating advantages of the film tube generator when used to generate high pressure steam in zones of high heat, may, and frequently will render this arrangement very desirable even though it may be necessary in some cases to sacrifice some thermal efficiency due to higher stack temperatures. Where a plurality of film tube generators are used, some in hot zones and others in cold zones, of course, there is no loss in thermal efficiency and the advantages of the film tube generator both from the standpoint of low heat head and high steaming capacity may be enjoyed. It should be understood that in every case it is necessary to make some compromise between ideal thermal efficiency and structural and economic factors. The best compromise for any particular plant installation may be determined by the engineer designing the installation and it is one of the important advantages of the present invention that it is applicable to a wide variety of installations and this flexibility of arrangement and construction makes it possible to re-design existing boiler units with a minimum of rebuilding and to so increase the efficiency of the installation as to, in many cases, add years of life to obsolescent units, which, however, frequently represent a very large capital investment.

The present invention is also of importance in connection with water walls; thus, for example, a film tube generator arranged as a water wall can be used very effectively for the generation of very high pressure steam, as it is exposed to the radiant heat of the flame and possesses, therefore, a very great steaming capacity while the high heat transfer efficiency of the generator adds a very desirable factor of safety against burning out. Installations in which one or more generators are operating as water walls are included in the present invention and are important embodiments thereof.

While the present invention is particularly concerned with installations in which a film tube generator is associated in series with a generator of the convection circulation type, it should be understood that two film tube generators can be connected together according to the present invention in order to generate steam of different pressures. Such installations can frequently be very efficiently arranged and where the difference in pressure is not too great, the drop in pressure through the injection orifices of the low pressure film tube generator may, in many cases, be sufficient to effect the desired drop in pressure between the two generators. In other cases, additional throttle valves must be provided and can be with advantage controlled by the amount of steam generated in

the low pressure generator by various control means such as water level controls and the like. A similar automatic control throttle is applicable to other embodiments of the invention and is illustrated in some of the drawings.

The drawings illustrate a few typical embodiments of the present invention and are purely diagrammatic in form as the exact structural design will vary with the installation and the proper arrangement and structure will be readily apparent to the engineer when confronted with the conditions of any particular installation. In the drawings, many common accessories such as safety valves, blow-offs and the like have been omitted in some cases and it should be understood that the drawings which are simplified to bring out the fundamentals of the present invention are not to be considered as limiting the invention to generators as illustrated, and, on the contrary, all the usual accessories will be employed wherever they are desirable. The drawings also show various circulation features associated with different types of conventional boilers. It should be understood that the association of one type of gas or water circulation with a particular type of conventional boiler in no sense limits the invention, as the drawings have merely been chosen to illustrate the most important types of circulation and a number of conventional boilers have been used in these illustrations in order to show the applicability of the present invention to these various types of boilers. It should be understood that features of flow shown in one figure as associated with one type of common boiler may be used with other types of boilers shown in other figures with a different type of circulation and vice versa.

The boilers of the present invention are illustrated in a purely diagrammatic form in the drawings, in which

Figure 12 is a section through a multiple unit Ladd type water tube boiler associated with a high pressure La Mont generator;

Figure 13 is a section through a cross drum 25 inclined water tube boiler associated with two La Mont generators with parallel and series gas flow respectively; and Figure 14 is a detail in perspective showing one of the headers broken away to show the jet orifices.

30 In the construction shown in Figure 1 two separate La Mont generators consisting in upper headers 1 and 2, lower headers or pots 3 and 4 and tubes 5 and 6 are arranged in the same furnace. Each generator has an independent circulating system. Thus, water and steam discharged from the lower header 3 flow through the pipe 7 into the pot 8, where steam is separated and taken off through the pipe 9 provided with a valve 10 and the water 35 flows through the pipe 11, pump 12 and pipe 13 into the upper header 1, thus completing the circuit for the high pressure boiler. Suitable valves 14 and 15 may be provided to regulate the flow in this circuit. In a similar manner 40 the steam and water discharged from the lower low pressure header 4 flow through the pipe 16 into the pot 17 where steam is separated and passes off through the pipe 18 controlled by the valve 19 and the water separated 45 flows through the pipe 20, pump 21 and pipe 22 to the upper low pressure header 2. A complete circulation is therefore provided for each boiler.

In addition to the separate circulations for 50 the two boilers a pipe 23, provided with a valve 24, connects the water space of the high pressure pot 8 with the water space of the low pressure pot 17 and water tends to feed through this pipe into the low pressure circulating system. The flow of water is controlled by the valve 24 which is in turn actuated by the water level control 25 on the pot 17, the amount of water fed being adjusted to the evaporation of the low pressure boiler. 55 Feed water for both boilers is taken in

through a pipe 26 controlled by a valve 27 which is actuated by the water level control 28 on the high pressure pot 8. All of the feed for both boilers therefore is introduced into the high pressure system and is controlled both by the evaporation of the high pressure generator and by the amount of feed which passes from the high pressure pot to the low pressure pot.

Gas flow through the two boilers is in series, first through the high pressure boiler and then through the low pressure boiler, resulting in a very economical action since the highly efficient heat transfer of the film tube generators brings the temperature of the gases substantially down to the temperature of the low pressure steam generated in the tubes 6. A single feed passes directly into the high pressure circulation and supplies both high pressure and low pressure generators with the amount of make-up water needed. The feed from the high pressure pot to the low pressure pot is automatically adjusted in accordance with the steam demands of the low pressure generator and in fact, actually enhances the steam capacity of this latter unit, since the water in the pot 8 may frequently be at a temperature above the boiling point of water under the pressure existing in the pot 17. Accordingly when the pressure is reduced in passing from pot 8 to pot 17 through the throttle valve 24, steam is formed which is added to the amount of low pressure steam generated by the low pressure boiler and passes off through the pipe 18. The operation of the two boilers is independent of their relative steam demands and the feed is automatically proportioned to the boilers in accordance with their demand, a steady uninterrupted feed is obtained irrespective of the relative steam demands on the two boilers and a very efficient utilization of the heating gases is achieved.

In the drawing, the feed is shown as introduced in to the suction of the La Mont circulating pump. This is a convenient and advantageous location for feed introduction, but the feed can be introduced into any other portion of the outside circulation of the La Mont generator or feed can be introduced into the high pressure water tube boiler.

Instead of feeding water from the high pressure unit to the low pressure unit the converse is also possible and is frequently desirable. This flow is shown in Figure 2, where a low pressure La Mont generator consisting in upper header 2, lower header 4 and tubes 6 is arranged in the stack or flue of an inclined tube boiler operating at a higher pressure. The water tubes are shown at 29 passing from rear headers 30 to front headers 31. The drum 32 is connected to the front headers through the pipes 33 and to the rear headers through the pipes 34, completing the circulating circuit of the boiler. The circula-

tion of the La Mont unit is from the header 4 through the pipe 16 to the pot 17 and thence through the pipe 20, pump 21 and pipe 22 back to the upper header 2. Steam is taken off from the pot through the pipe 18 controlled by the valve 19. Part of the excess water of the La Mont circulation is pumped from the water space of the pot 17 into the back header 30 of the high pressure boiler by means of the pump 35 drawing water through the pipe 36 and discharging it through the pipe 37, valves 38 and 39 being provided in the respective pipes for control.

Feed water for both boilers is injected into the circulation of the La Mont boiler through the feed pipe 40 controlled by the valve 41 which, in turn, is actuated by the water level control 42. In operation all of the feed water for both boilers is circulated through the low pressure La Mont boiler and is heated up so that the water tube boiler operating at high pressure receives only heated feed water. The La Mont generator, therefore, not only serves the purpose of an efficient source for low pressure steam but it also serves to heat up all of the feed water which is introduced into the high pressure boiler. Owing to the large amount of cold feed water which is injected into the circulation of the La Mont generator, the temperature of the water in the upper header 2 is comparatively low and it is therefore readily possible to operate with a heat head on the La Mont tubes which is less than zero; that is to say, the stack gases after leaving the La Mont generator are at a temperature below that of the low pressure steam generated.

In addition to increasing the over-all efficiency of the boiler installation by generating low pressure steam by means of what may really be considered as the waste heat from the high pressure boiler, and particularly in carrying stack temperatures down to an exceedingly low point by operating the La Mont generator as a feed water heater as well as a generator, a further advantage is inherent in the construction shown in Figure 2, namely, the increased efficiency of circulation in the water tube boiler. The water injected through the pipe 37 possesses considerable velocity and can, if desired, be so directed as to flow into the water tubes in the form of jets at considerable speed. A semi-injector action results which greatly enhances the effectiveness of the ordinary convection circulation which exists in inclined tube boilers of the type shown. The construction therefore, is very efficient from the standpoint of utilizing the heating gases and at the same time increases the circulation and therefore the efficiency of the high pressure boiler itself.

In Figure 3, a somewhat similar design of installation is shown but instead of providing an independent circulation for the low pressure La Mont generator and merely feed-

ing the excess water into the high pressure water tube boiler, a series parallel circulation is provided, water under high pressure being taken from the forward end of the drum 32, through the pipe 43, into the upper header 2 of the La Mont generator. In other words, the water for the La Mont generator is circulated through the water tubes of the inclined tube generator and thence in series through the La Mont generator. This greatly enhances the circulation efficiency in the inclined water tube generator itself and at the same time omits the additional pump required in the modification shown in Figure 2 in order to provide for a separate circulation in the La Mont generator. Feed can be introduced through the pipe 44 and the La Mont generator can be utilized therefore as a feed water heater as well as a generator, effecting the economical savings described in connection with the modification shown in Figure 2.

Figures 4 and 4a represent a very advantageous combination of a La Mont generator with a relatively inefficient and at the present time almost obsolete or obsolescent type of vertical fire tube generators. The fire tube generator consists in a shell 45 extending down to form water legs 46 and 47 separated by baffles or partitions 217, and provided with fire tubes 48. The La Mont generator, which is operated at a higher pressure than is the fire tube boiler, consists in an upper header 51, lower header 53 and tubes 55, which tubes pass through the fire tubes, resulting in a very markedly decreased hydraulic mean depth and increased velocity of heating gases through the fire tubes. Steam and water is discharged from the lower header 53 into pot 54, where steam is separated, the steam passing off through the pipe 49 controlled by the valve 50 and the water flowing into the leg 46 of the fire tube boiler through the pipe 52 provided with the valve 225 controlled by the water level control 226. Water is taken from the leg 47 through the pipe 56 and forced by the pump 57 through the pipe 58 into the upper header 51 of the La Mont generator. Valves 59 and 60 control the flow. In operation water is thus taken from the one leg of the fire tube boiler, passed through the La Mont generator at higher pressure, the steam generated taken off through the steam pipe 49, the excess water flowing into the other leg of the fire tube boiler. Thus, the circulation of water through the La Mont generator passes in series through the fire tube boiler and enhances the circulation of the latter in addition to very greatly increasing the efficiency of both units, due to the fact that the La Mont tubes pass through the fire tubes and thereby permit a very low hydraulic mean depth and high gas velocity with a correspondingly increased heat transfer efficiency. Low pressure steam is taken

from the fire tube boiler through the pipe 61 controlled by the valve 62.

In the modification shown in Figure 5, a low pressure La Mont generator is installed in the stack of a bent tube cross drum boiler installation of the Stirling type, which boiler in this modification operates at a considerably higher pressure than does the La Mont generator. The Stirling boiler consists in upper drums 63, 64 and 65 and lower drums 66, which is connected with the drum 63 by the tubes 67 and to the drums 64 and 65 by the tubes 68 and 69. Steam spaces of the upper drums are connected by the tubes 70 and 71 and the water spaces of the drums 64 and 65 are connected by the tube 72.

The La Mont generator consists in upper header 73, lower header 74 and tubes 75. Water and steam from the header 74 of the La Mont generator pass through the pipe 76 into the pot 77, where the steam is separated and passes off through the pipe 78 controlled by the valve 79. Water from the water space of the pot is pumped through the suction pipe 80, pump 81 and pipe 82 into the upper header 73, thus providing a separate complete circuit for the La Mont generator. Valves 83 and 84 control the speed of circulation.

Feed water is introduced into the drum 63 of the Stirling boiler through the pipe 85 and the feed is controlled by the valve 86 actuated through the water level control 87 connected to the drum 64. Water is also fed from the drum 65 through the pipe 88 into the pot of the La Mont generator and serves as make-up water to replace the steam generated in the La Mont generator. The flow through the pipe 88 is controlled by the throttle valve 89 actuated by the water lever control 90. The circulation of the two boilers are separate but the feed for both boilers is carried in series through the Stirling boiler and greatly enhances the natural convection circulation which takes place in this boiler. The advantages of series gas flow with the efficient La Mont generator in the stack are retained in this modification, which is very suitable for installations which already have bent tube boilers of the Stirling type. It is possible to mount a La Mont generator in the stack with a minimum of redesigning and rebuilding, and a large increased overall efficiency results, both from the more efficient utilization of the heat in the heating gases and from the increased circulation in the Stirling boiler which correspondingly increases its steaming capacity and improves its operation. The water discharged through the pipe 88 is usually at a temperature considerably above the boiling point corresponding to the pressure which exists in the pot 77 and therefore, a considerable amount of water is turned into steam and passes off as low pressure steam through the pipe 78. A sudden increased demand for low pressure steam, therefore, low-

ers the water in the pot and increases the opening of valve 89 with the result that an additional volume of steam is generated due to the partial evaporation of the water fed from the Stirling boiler. It is thus possible to take care of comparatively large fluctuations in demand for low pressure steam with a La Mont generator of small and economical size. Only a single pump is used and the system is simple and reliable in operation and lends itself to many industrial applications.

A combination of a Scotch marine boiler and a separately fired La Mont generator is shown in Figure 6. The Scotch boiler which is of conventional design, consists in a shell 91 extending in the form of a leg 92 surrounding the firebox, and provided with fire tubes 93. Feed is introduced through the pipe 94 controlled by the valve 95 and steam is taken off from the steam space through the pipe 96 controlled by the valve 97. The Scotch marine boiler which may advantageously operate at a moderate steam pressure is associated with a high pressure separately fired La Mont generator consisting in an upper header 219, lower header 220 and tubes 221, the circulation being from the header 220 through the pipe 222 into the pot 223 and thence through the pipe 224, pump 98 and pipe 99 into the upper header of the La Mont generator. Valves 100 and 101 are also provided for controlling the flow.

In addition to the separate circulations of the La Mont boiler and the ordinary convection circulation of the Scotch boiler means are provided for feeding water from the leg 92 of the Scotch boiler into the pot 223 by means of the pump 102 drawing water from the bottom of the leg 92 through the pipe 103 and discharging it through the pipe 104, valves 105 and 106 being provided for control purposes.

A relatively clean, hot feed is thus provided for the La Mont generator which is advantageous when it is desired to generate large quantities of high pressure steam in a La Mont generator of economical size. Owing to its high heat transfer capacity it is also possible to use heat sources of great intensity without danger of burning out the tubes. Not only is a hot feed water of desirable purity assured for operation of the La Mont generator at high pressure but the circulation in the Scotch marine boiler is very greatly enhanced as the flow through this boiler is from the feed pipe 95 backward and down through the leg 92 and then out through the pipe 103 into the pot of the La Mont generator. The flow of water thus roughly is counter to the flow of heating gases up through the combustion space and through the fire tubes resulting in an effective heat transfer and decreasing the stack temperatures of the gases leaving the Scotch boiler. This counter flow can, in some cases, material-

ly increase the efficiency of the boiler, as stack temperatures are apt to run economically high owing to the relatively short travel through the fire tubes which also are not very effective heat exchange surfaces because of their large hydraulic mean depth. The combination therefore, renders the operation of the Scotch boiler more efficient and at the same time provides for a reliable hot feed for the high pressure La Mont generator.

The high heat transfer capacity of La Mont generators renders them particularly efficient as water walls or radiant heat boilers and an efficient and desirable combination of water wall boiler and conventional inclined water tube boiler is shown in Figure 7. In this figure, the water tube boiler consisting in a drum 107, rear header 108, front header 109 and tubes 110 and baffles 111, preferably operates under moderate pressure, steam being taken off from the steam space of the drum through the pipe 112 controlled by the valve 113. The low pressure La Mont water wall boiler consists in upper header 114, lower header and pot 115 and tubes 116. High pressure water from the rear header 108 flows to the header 114 through the pipe 117 controlled by the throttle valve 118. After passing through the generator tubes 116, the mixture of steam and water is separated in the pot 115, the steam passing off through pipe 119 controlled by valve 120 and the water being pumped by the pump 121 through the pipes 122 and 123 into the water space of the drum 107, suitable valves 124 and 125 being provided to control flow.

The La Mont generator efficiently shields the walls and serves as an efficient source of low pressure steam. At the same time the circulation through the main boiler is enhanced due to the fact that water is pumped into one end of the drum and taken out from the rear header 108 at the other end of the drum. A further important advantage lies in the fact that the danger of burning out the tubes 116 is minimized due to the fact that a large volume of high pressure water is available for feeding these tubes directly and is instantly controlled by the valve 118 which is actuated by the water level control 126. There is therefore, little or no danger of burning out these tubes even with very marked and sudden variations in the temperature of the fire and in the demands for low pressure steam.

If desired, the water wall can be operated as a full tube water wall instead of a film tube water wall. While full tube operation does not give the advantages of high steaming capacity which are possessed by film generators, the rapid circulation provides for ample protection of the tubes and in some cases the construction may be cheaper and where the demand for low pressure steam is not great, it may be economically advantageous to con-

struct full tube water wall generators, instead of film tube generators.

In Figure 8, a separately fired high pressure La Mont generator is shown associated with an ordinary Wickes boiler designed to generate steam at a lower pressure. The Wickes boiler consists in an upper drum 127, lower drum 128 connected by rear circulating tubes 129 and front circulating tubes 130. A baffle 131 separates the two sets of tubes. The steam is taken off from the steam space of the upper drum through the pipe 132 controlled by the valve 133 and a feed pipe 134 provided with a valve 135 is also connected to the water space of the upper drum. This feed pipe is used for auxiliary feeding, as will be described below.

The separately fired high pressure La Mont generator consists in an upper header 136, lower header 137 and generating tubes 138. Water and steam from the lower header 137 pass through the pipe 139 to the pot 140, where steam is separated and part passes off through the steam pipe 141 controlled by the valve 142. Excess water from the water space of the pot is circulated through the pipes 143 and 144 by the pump 145 which forces the water into the upper header 136. Valves 146 and 147 are provided to regulate flow and feed water is introduced through the pipe 148 controlled by the valve 149, which is actuated by the water level control 158.

Some of the high pressure steam from the pot 140 is passed through the pipe 150 and injector 151 where it picks up feed water from the tank 152 through the pipe 153 and injects this feed water at high velocity through the pipe 154 and nozzles 155 into the bottom of the water tubes 130 of the Wickes boiler, thereby very greatly enhancing the speed of circulation in the Wickes boiler and correspondingly increasing its steaming capacity. The amount of feed water injected into the Wickes boiler by the high pressure steam is controlled by means of the throttle valve 156 actuated from the water level control 157 associated with the upper drum of the Wickes boiler. Feed into the La Mont generator is similarly controlled by a water level control 158 associated with the pot 140.

In operation the circulation through the La Mont generator is substantially independent from that of the Wickes boiler as far as the water is concerned, and high pressure steam can be generated in varying amounts according to demand. The demand for low pressure steam from the Wickes boiler produces variations in the water level in the upper drum and this in turn actuates the throttle valve 156, causing the injection of the necessary feed water by means of high pressure steam from the La Mont generator. Particularly where there is a large difference in pressures between the two boilers a very

violent injection will take place and the naturally sluggish convection circulation of the Wickes boiler is greatly accelerated. The best results are produced when nozzles 155 are used, so that the injected feed water at high velocity is carried directly up the main steaming tubes of the boiler, sucking with it of course, water from the lower drum. In some cases, where such a rapid circulation of water in the Wickes boiler is not necessary, a somewhat cheaper and simpler construction can be used in which the nozzles are omitted and the feed water is simply injected into the bottom of the drum below the tubes 130. This will increase the circulation due to the fact that the velocity of the injected water continues into the circulating tubes.

The arrangement of a Wickes boiler with a separately fired La Mont generator is very flexible and the relative sizes of the two units can be varied within wide limits. It is also possible to operate either generator separately from the other; thus, for example, if connection to the Wickes boiler is shut off by closing the valve 156 the La Mont generator can be operated entirely independently and in the same way the Wickes boiler can also be operated independently, utilizing a separate feed through the pipe 134 controlled by the valve 135. In some cases, it may be desirable to provide a very small La Mont generator where the demands for high pressure steam are low or the La Mont generator may be run at varying loads and, at times, the steam production may be insufficient to inject sufficient feed water into the Wickes boiler even when the whole of the high pressure steam is used for this purpose. The deficiency can then be made up by introducing some additional feed water through the pipe 134 if desired. In general, it should be understood that control of feed water which has been illustrated as automatic in some figures and as manual in others can be widely varied between the limits of full automatic control and full manual control.

The combination of two La Mont water wall generators for high pressure steam with a lower pressure Edgemoor single pass boiler is shown in Figure 9. The front water wall consists in an upper header 159, generating tubes 160 and lower header or pot 161 and the rear water wall similarly consists in an upper header 162, generating tubes 163 and a lower header or pot 164. The Edgemoor boiler is provided with an upper steam and water drum 165, a lower drum 166, generating tubes 167, a rear steam and water drum 168, a water heater 169 and a superheater 170. The steam space of the drum 165 is connected to the steam space of the drum 168 by means of the pipe 171 and the water spaces of these two are similarly connected by the tube 172. Saturated steam at low pressure can be taken off through the pipe 173 con-

trolled by the valve 174 or it can be passed through the superheater 170 passing out through the superheated steam main 175 controlled by the valve 176. Feed water is introduced through the pipe 177 controlled by the valve 178.

Instead of connecting the drum 166 to the drum 168 by circulating tubes as in the ordinary design of Edgemoor boiler the circuit is broken and the tube (or tubes) 179 which, in the ordinary construction would extend to the drum 166, is connected to the inlet of a pump 180. The pump in turn forces the water through the pipes 181, 182, and 183 into the upper headers of the La Mont water wall generators. The circuit is completed by connecting the water spaces of the pots 161 and 164 to the drum 166 of the Edgemoor boiler through the pipe 184 controlled by the throttle valve 185. High pressure steam is taken off from the pots 161 and 164 through the pipes 186 and 187 controlled by the valves 188 and 189. Valves 190 and 191 are also provided in the pipes 182 and 183 in order to control the delivery of water to the La Mont generators. These valves may be operated manually or, as shown in the drawing, may be connected to suitable water level controls on the pots 161 and 164. These water level controls are shown at 192 and 193.

In operation feed water for both of the boilers is introduced through the pipe 177 heated in the feed water heater 169, whence it passes into the drum 168 and down through the pipe 179. The pump 180 then delivers the water at a considerably higher pressure into the La Mont generators where part of the water is evaporated and steam and water are separated in the pots 161 and 164. The excess water is then circulated through the pipe 184 into the bottom drum of the Edgemoor boiler and thence positively upward through the generating tubes 167 into the upper drum 165, where steam and water are partially separated, the steam and water passing through pipes 171 and 172 into the steam separating drum 168. The water then circulates down through the pipe 179 and again through the La Mont generators.

It will be seen that the water circulation through the generators at different pressures is purely in series, every bit of the circulating water being required to pass through the generators at both pressures in series. This provides for an extremely efficient circulation through the Edgemoor boiler and very greatly increases its steaming capacity. At the same time the large feed water heater of the Edgemoor boiler serves to heat up feed water for both the Edgemoor and the La Mont generators. Only a single pump is required in this system and yet a full positive circulation is assured in all three generators.

Figure 10 illustrates three La Mont gener-

5 ators arranged in series in the same furnace and possessing a pure series circulation. The high pressure generator which is arranged in the hottest zone of the furnace consists in upper header 194, tubes 195 and lower header or pot 196. Correspondingly the intermediate pressure generator includes upper header 197, tubes 198 and lower header or pot 199, whereas the low pressure generator which is in the coolest zone is shown as provided with upper header 200, tubes 201 and lower header or pot 202. Each of the pots is provided with steam pipes from their steam space, the high pressure pot discharging high pressure steam through the pipe 203 controlled by the valve 204, the intermediate pot through pipe 205 controlled by valve 206 and the low pressure pot through pipe 207 controlled by valve 208.

20 Water from the low pressure pot 202 passes through a pipe 209 into reservoir 227 from which it is drawn by pump 210 and forced through a pipe 211 into the upper header 194 of the high pressure generator. 25 A large excess of water is circulated through this generator, a certain amount being evaporated and the steam separated in the pot 196. The water which remains unevaporated passes then from the water space of the pot 196 through the pipe 212 into the upper header 197 of the intermediate pressure generator, whence it circulates down through the film tubes 198, a still further portion of water being evaporated and the steam separated in the pot 199. The unevaporated water and also some steam passes from the water space of the pot 199 into a reservoir 8 which is similar to that shown in Figure 1, where steam and water are separated, the 30 water passing thence through the pipe 218 into the upper header 200 of the lower pressure generator, where a still further amount is evaporated and the steam separated in pot 202. The excess water is recirculated 35 through pipe 209 into reservoir 227 where any entrained steam is separated and passes into the steam main 207 through the pipe 228. Feed water may be introduced into the reservoir 227 directly but preferably such 40 introduction is controlled by means of an injector 151 operated from steam from the high pressure generator. This feed water is taken from a tank 152 and passes into the system through the pipe 153 to an injector 45 151, the steam for which is led from the reservoir 8 by the pipe 150. A water level control 216 acts upon valve 215 in the pipe 150 so that the water level in the reservoir 227 determines when the valve 215 shall open 50 and permit the high pressure steam to inject water into the system.

55 It will be seen that the circulation is purely in series and is at all times counter to the gas flow. This provides for a maximum efficiency from a thermal standpoint, as the

lowest pressure steam is generated in the coolest zone and the heat units contained in the heating gases are absorbed with a maximum of completeness. The system is simple, requiring only a single pump and a single control and due to the fact that all of the water for the three generators is circulated through the high pressure tubes which are exposed to the most intense heat they receive the maximum protection. The intermediate 70 generator is correspondingly protected by its proportionate excess of water.

75 The drop in pressure between the generators is produced in the modification shown in Figure 10 by the restriction of the inlet 80 orifices in the headers 197 and 200 when the difference in pressure between the various generators is not excessive. This arrangement is very simple and economical, as it involves no moving parts or valves.

85 Owing to the fact that all the water is circulated in series through the three generators a stoppage in either the high or intermediate pressure generators might cause the low pressure generator to run dry and burn out and in order to prevent this possibility by-pass pipes 216 and 217 can be provided leading from the pump outlet to the upper headers 197 and 200 and controlled by the valves 218 and 219. In case of a partial or 90 total stoppage of flow through the high pressure or intermediate pressure generator, one or more of these valves can be opened to produce a parallel circulation through the intermediate or low pressure generators and prevent 95 their burning out.

100 In a similar manner, these valves may be used to modify the pure series circulation and produce in part a series parallel circulation. This may be desirable where the demands for low pressure or intermediate pressure steam may vary and may, at times, be disproportionately large in comparison to the demands for high pressure steam. The exact combination of controls, automatic, semi-automatic or manual, which is most desirable under the operating conditions in any particular installation will, of course, be chosen by the skilled steam engineer.

105 Figure 11 illustrates the combination of two inclined cross drum water tube boilers operating under different pressures. The high pressure boiler consists in drum 229, front headers 230 and 231, rear headers 232 and 233, the headers being connected respectively by two decks of generator tubes 234 and 235. The upper rear header 232 is connected to the drum 229 by the tubes 236 and the respective front and rear headers are connected by the pipes 238 and 237. A superheater consisting in intake header 239, superheater tubes 240 and outlet header 241, is connected to the steam space of the drum 229 by the pipe 242 and discharges high pressure superheated steam through the pipe 243 into a 110 120 125 130

high pressure turbine 244. The boiler is baffled to produce a heating gas flow as indicated by the arrows and results in three passes through the main or upper deck of generating tubes, the heating gases finally passing out through the flue 245 into the low pressure furnace 246.

The low pressure generator is similar in design to that of the high pressure generator and contains a drum 247, rear headers 248 and 249, front headers 250 and 251, an upper deck of generating tubes 252, a lower deck of generating tubes 253, return circulation tubes 254 and a superheater consisting in an intake header 255, tubes 256, an outlet header 257 and an intake steam pipe 258 from the drum 247. Superheated steam is discharged from the outlet header 257 into the pipe 259.

The gas flow through the low pressure generator is similar to that in the high pressure generator, and is indicated by arrows. A fan 260 is provided in the stack 261 in order to assist the draft through both generators.

The exhaust steam from the high pressure turbine 244 which may advantageously be at about the same pressure as the steam from the low pressure generator, passes through the pipe 262 into the pipe 259 where it mixes with the superheated low pressure steam from the low pressure generator with a corresponding improvement in quality or degree of superheat and the mixed low pressure steams then pass through the low pressure turbine 263 and are exhausted through the pipe 264.

A cross circulation from the low pressure generator to the high pressure generator is effected by the pump 265 which takes water from the water space of the drum 247 through the pipe 266 and discharges it through the pipe 267 into the cross header or under drum 326 connected to the front headers 231 of the high pressure generator. Water may be returned from the steam space of the drum 229 through the pipe 268 and throttle valve 269 into the cross header 270 which is connected to the front headers 251 of the low pressure generator. When the valve 269 is opened a double series parallel circulation is effected and a considerable enhancement of the steam generating capacity of the low pressure generator is brought about due to the fact that the incoming water into the mud drum 270 is not only at a high pressure but also at a temperature which is usually considerably higher than that corresponding to the steam pressure in the low pressure generator. Accordingly in rising through the headers 251 and 250 considerable steam is formed due to reduction of pressure and an increased production of low pressure steam results. The cross circulation also materially enhances the natural convection circulation in both of the generators and their efficiency is correspondingly increased. Feed may be taken into one

or both of the generators as desired through the pipes 271 and 272 controlled by the valves 273 and 274 respectively.

The high heat transfer capacity of film tube generators of the La Mont type, together with their structural advantages as high pressure generators makes it possible to combine a high pressure film tube unit with conventional water tube boilers, the film tube generator being heated by the stack gases from the ordinary water tube generators. Such a construction is shown in Figure 12 where two heavy duty Ladd type water tube boilers are combined with a film tube generator arranged in the stack. 80

The two Ladd boilers consist in upper drums 275 and 276, lower drums 277 and 278 and connecting tube bundles 279, 280, 281, 282, 283 and 284. Baffles 285 and 286 are provided in the drums 277 and 278 in the usual manner, so that the tubes 279 do not connect with the main space of the drum 277 and in a similar manner the tubes 284 do not connect with the main space of the drum 278. Superheaters are provided for each of the 90 boilers, one superheater consisting in headers 287 and 288 connected by superheater tubes 289 and provided with a steam connection 290 from the drum 275, the other superheater consisting in headers 291 and 292 connected by superheater tubes 293 and provided with a connection 294 from the steam space of the drum 276. Superheated steam from the outlet headers 288 and 292 passes through the pipe 295 into a common superheated steam 100 main 296.

The La Mont generator consist in an upper header 297, lower header 298 and generating tubes 299. The La Mont superheater is shown as provided with an upper header 300, 105 lower header 301 and superheater tubes 302. A pipe 303 connects the steam space of the lower header 298 with the upper header of the superheater. Superheated steam passes from the lower header 301 through the pipe 110 304 into the high pressure turbine 305.

Water for the La Mont generator is circulated by the circulating pump 306 through the pipe 307 into the upper header 297 and excess water in the lower header or pot 298 flows down through the branch tubes 308 and 309 into the spaces of the drums 277 and 278 which connect with the tubes 279 and 284 respectively. Flow through the pipes 308 and 309 is controlled by the valves 310 and 311 which are actuated by the water level control 312 which operates on the lower header 298. 115

After passing through the high pressure turbine the high pressure steam from the La Mont generator may be at a pressure approximately the same as that obtaining in the low pressure steam main 296 and the steam from this main is mixed with the exhaust steam from the high pressure turbine in the pipe 313, thus improving the quality of exhausted 120 steam. 125

steam from the high pressure turbine by reason of the superheat in the low pressure steam. The mixed steams are then passed through the lower pressure turbines 314 which exhaust through the pipe 315 into the condenser 316. Instead of utilizing the superheat of the low pressure steam for improving the quality of the expanded high pressure steam, the latter can be expanded to a pressure somewhat above that of the low pressure steam and then permitted to expand through a reducing valve, which will result in improving the quality of the steam or in some cases in actually superheating it, provided, of course, the pressure of the steam exhausted from the high pressure turbine is not too high, as the heat content of steam does not increase indefinitely with the pressure, but after a certain point, an increase in pressure actually results in a decrease in heat content. Of course, steam which is at a sufficiently high pressure will not be superheated on expanding it through a nozzle. At the pressures which would usually be used in the low pressure units, however, such expansion will ordinarily result in superheating the expanded steam or in improving its quality. Other methods of insuring a steam of satisfactory quality for use in the low pressure turbine may also be used.

Condensate flows out through the pipe 317 and is pumped into the feed tank 318 by the condensate pump 319.

From the feed tank 318 a feed pump 320 forces the water into the feed system or the pipe 321 at a pressure slightly less than that obtaining in the low pressure generators. The main water spaces of the drums 277 and 278 are connected to the pipe 321 through the pipes 322 and 323 which pipes are provided with check valves 324 and 325. The water discharged from the pump 320 together with the water which flows through the pipes 322 and 323 all passes to the pump 306 and by it is circulated through the La Mont generator. Feed is injected into the pipe 307 at any suitable point.

It will be seen that water is circulated through the La Mont generator where part is evaporated, thence into the baffled portions of the drums 277 and 278, whence it ascends the tubes 279 and 284 and discharges into the drums 275 and 276 accompanied by considerable steam as the water discharged from the La Mont generator is at a temperature higher than that corresponding to the steam pressure in the Ladd boilers and considerable ebullition takes place in the tubes 279 and 284. The water then tends to drop from the drums 275 and 276 through the tubes 280 and 283 into the drums 277 and 278 again ascending through the main steaming tubes 281 and 282, producing the regular convection circulation in Ladd type boilers. This circulation is enhanced by the fact that water is

being constantly drawn out from the drums 277 and 278 below the discharge point of the down circulating tubes 280 and 283 and flows out through the pipes 322 and 323 to be recirculated through the La Mont generator. A greatly increased speed of circulation in the Ladd boilers is thereby achieved and the capacity of the boilers is correspondingly enhanced. The increased speed of circulation through the Ladd boilers also has the advantage that the formation of scale on the boiler tubes is greatly minimized and at the same time the more rapid circulation aids in preventing steam locking, particularly when the generators are forced.

Condensate which is at a relatively low temperature together with cold feed water forms a considerable proportion of the water volume pumped into the upper header 297 of the La Mont generator. The average temperature of this water being so low a heat head less than zero can easily be obtained in the La Mont generator which results in a lowering of the stack temperature to a very economical point. In the specification and claims of this application, the expression "heat head" is used to define the temperature differential between the stack gases and the saturated steam generated in the generator. At the same time high pressure steam is produced in the La Mont generator and is efficiently utilized in the small compact high pressure turbine. The advantages of the La Mont generator as a heat transfer apparatus and as a high pressure generator are thus utilized in a single installation and marked increase in economy can be effected.

An even more important advantage of the combination shown in Figure 12 lies perhaps in the great increase in steaming capacity which is effected by combining the La Mont generator with the two Ladd boilers. As is well known, it is not possible to force water tube boilers beyond certain ratings without greatly increasing the stack temperatures and correspondingly decreasing the over-all efficiency of the installation. A further disadvantage which is entailed in forcing the common types of water tube boilers without enhancing the speed of circulation lies in the fact that there is a considerable tendency for some of the tubes in the hottest zones to steam locally, that is to say, to produce a layer of steam between the metal of the tube and the main body of the water which of course presents considerable danger of burning out the tubes. When, however, the speed of circulation is markedly enhanced, as is the case in Figure 12, the danger of steam locking is greatly minimized or completely removed, even when the Ladd boilers are forced to ratings very much higher than those ordinarily used. When, however, a high pressure La Mont generator is placed in the stack it is possible to force the Ladd boilers to ex-

traordinarily high ratings without any loss in efficiency since the La Mont generator reduces the stack temperature to a very low point even though the initial stack temperature of the gases leaving the Ladd boilers may be comparatively high. It is thus possible by arrangements such as those illustrated in Figure 12 to greatly increase the power capacity of large water tube boiler installations without loss in efficiency and in many cases with a marked gain in efficiency. Not only is heating surface of high steaming capacity and capable of producing high pressure steam introduced into the stack or flue, but the circulation of the water tube boilers themselves is very notably improved which, in its turn, results in greater steaming capacity of the water tube boilers themselves and aids in prevention of steam locking and sealing troubles.

Figure 12, as is the case in the other figures, is purely diagrammatic in character and many useful and necessary accessories have been omitted in order to improve the clarity of the drawings. Thus, for example, the superheater tubes 289 and 293 are shown as having but a single coil. In actual installations it will usually be desirable to provide a plurality of coils in order to increase the surface but in the drawings a single coil only has been shown in order to make the operation more clear. The high pressure steam after passing through the high pressure turbine is shown as mixing directly with the superheated low pressure steam and in many installations this is very advantageous as the only changes necessary are the installation of the La Mont generator in the stack and of the high pressure turbine, together with a new pipe connection. Existing plants can thus be redesigned with a minimum of rebuilding.

This arrangement is, however, not the only one possible and in some cases may not be the most advantageous. Thus, when there is a very large drop in pressure through the high pressure turbine the quality of the steam may be very poor as it is not possible to use as high superheats with high pressure steam as with low pressure steam because the materials used in the generator and turbine and their associated elements show a marked loss in strength when the temperature exceeds certain maximum figures. In such cases it may be very advantageous to reheat the exhaust steam from the high pressure turbine in a re heater which may be associated either with the La Mont generator in the stack or may be heating surface connected with the low pressure boilers and may be any suitable type of superheater. Such a reheat either to a temperature as high or higher than the original superheat, or to a lower temperature may be used and a plurality of such reheat may also be used where they

should prove desirable. In fact all the advantages of differential reheat which are described in my co-pending application, Serial No. 101,041, filed April 10, 1926, may be combined with installations such as those shown in Fig. 12 and the same applies, of course, also to installations of the type illustrated in Fig. 11.

It will be noted that the spacing of the tubes in the La Mont generator shown in Fig. 12 are so arranged as to produce a gradually decreasing gas passage cross-section. This is of advantage as gas velocities and correspondingly heat transfer efficiencies are maintained at a high level despite the fact that the volume of the heating gases shrinks as they are cooled in passing through the generator. A similar proportioning of gas passage cross-section may be advantageous in many of the other types of installations illustrated in the other figures and it should be understood that wherever desirable this feature may be embodied in installations in accordance with the principles of this invention.

Fig. 13 illustrates two low pressure generators with series gas flow combined with a high pressure generator receiving its gas in parallel from the first of the low pressure generators. The first low pressure generator, which is of the cross drum inclined water tube type, consists in a drum 327, rear headers 328, mud drum 354 connected to the bottom of the rear headers, generating tubes 329 and front headers 330. These latter are connected to the drum 327 through the tubes 331. The boiler is baffled so that gas passes as is indicated by the arrows, making three passes through the tubes and thence being conveyed through the flue 350 to the second low pressure generator which is shown as of the film tube type consisting in an upper header 342, lower header 343 and generating tubes 344. Water is introduced into the upper header through the pipe 355 by means of a pump 347 which receives feed water from the pipe 348.

A high pressure film tube generator is shown as connected in a parallel flue and consists in upper header 332, lower header 333 and generating tubes 334. Gas is taken from the bottom of the third pass in the first low pressure generator through the flue 336 controlled by the damper valve 337 and the corresponding damper 358 in the flue 350 and after passing over the generating tubes of the high pressure generator, it passes through the flue or duct 349 into the flue 350, uniting with the stack gases from the low pressure generator and thence passing in series through the second low pressure generator.

Circulation for the high pressure generator is provided by means of a pump 338 which takes water from the water space of the lower header or pot 343 and also from

the water space of the drum 327 through the pipe 340. The water is forced into high pressure generator through the pipe 339 into the upper header 332, whence it passes down 5 through the generating tubes 334 into the lower header or pot 333 where the steam is separated. The steam produced passes out through the high pressure steam main controlled by the valve 352 while the unevaporated water passes through the pipe 335 into the mud drum 354, a suitable valve 356 being provided to regulate the flow. Low pressure steam is taken from the steam space of the drum 327 through the pipe 346 into the low 10 pressure steam main 345 which leads from the steam space of the low pressure film tube generator. A valve 353 is placed in this pipe between the point of junction with the pipe 346 and the pot 343.

20 In operation, gases pass in series through the first two passes of the cross drum boiler and then the gas flow is divided, a portion passing through the third pass of the cross drum boiler and into the flue 350, while a 25 second portion passes through the flue 336 and the high pressure generator into the flue 349, joining the remainder of the gases in the flue 350. The gases in the flues 349 and 350 may be of the same temperature or may 30 be of different temperatures. In either case, the reunited gases pass in series through the low pressure film tube generator where their temperature is still further reduced and they 35 pass off into the stack.

35 Water circulation in the cross drum boiler is partly confined within the boiler itself and partly passes in series through the high pressure generator, water being sucked out of the water space in the drum 327 through the 40 pipe 340 and thence forced into the generating tubes of the high pressure generator by means of a pump 338. The unevaporated water delivered to the pot 333 passes through the pipe 335 into the mud drum 354, the 45 amount flowing through and the pressure being regulated by the valve 356. This series parallel flow very greatly increases the speed of circulation in the cross drum boiler as hot water under high pressure is introduced in the rear headers and greatly accelerates the flow through the generating tubes, this circulation being still further assisted by the withdrawal of water through the pipe 340. Valves 357 are provided in the connections between the drum 327 and the headers 50 328 and may be partly or completely closed. When they are closed, the circulation through the cross drum boiler and the high pressure film tube generator is purely in series. The proportion of water which is circulated in series through the two generators can be varied by suitable adjustment of the valves. Where a straight series circulation is 55 not desired, but it is wished to prevent a reverse circulation in the cross drum boiler,

check valves can be substituted for the valves 357, permitting water to flow from the drum 327 to the headers 328, but preventing the reverse flow.

Feed water for all three boilers is introduced through the pipe 348 into the circulating system of the low pressure film tube generator and all of the feed water is passed in series through this generator into the high pressure generator and thence into the low 70 pressure cross drum boiler. The low pressure film tube generator may be used as a straight water preheater or economizer by closing the valve 353, in which case no steam is generated, or what little steam is generated is passed into the high pressure boiler with the unevaporated water. Owing to the great heat transfer efficiency of the film tubes, it is possible to produce a very low heat head 75 and usually substantially below zero, bringing the temperature of the heating gases down to an extremely low figure and thus utilizing a maximum number of heat units in the gases.

Where, as in many cases, it is desirable 80 to utilize the efficient heat transfer surface presented by the film tube generator for the purpose of generating low pressure steam, this can be effected by a suitable proportioning of heating surfaces and by a suitable 85 forcing of the first low pressure generator in order to supply sufficient heat. In this latter case, steam is advantageously generated at the same pressure as in the cross drum boiler and by opening the valve 353, 90 this low pressure steam can be introduced into the low pressure steam main. The same arrangement of generators can be used with varying loads and demands for low pressure steam, the second generator acting as a 95 100 straight preheater or economizer on light loads where the cross drum boiler is not being forced to a very high rating and where correspondingly the temperature and quantity of the gases passing through the flue 350 is 105 not very great. When, however, the demands for low pressure steam or high pressure steam or both are materially increased, and, correspondingly, one or both of the cross drum 110 and high pressure La Mont generators are 115 being forced to a high rating, the temperature in the flues 350 and 349 rises and the quantity of gas flowing may also rise, particularly where forced draft is used. The 120 amount of heat passing through the second or low pressure La Mont generator will, therefore, very rapidly increase and will usually increase at a very much higher rate than the increase of feed through the same generator due to enhanced steam demands 125 in the cross drum boiler and the high pressure generator. It will then be advantageous to utilize the low pressure La Mont generator as a steam generator as well as a preheater or economizer and this can be effected as 130

has been pointed out above by opening the valve 353.

It will be apparent that the arrangement is very flexible and varying demands for high and low pressure steam can be simply and almost instantly complied with by variations in the relative amounts of gas passing through the third pass of the cross drum boiler and through the high pressure La Mont generator and by generating more or less low pressure steam in the low pressure La Mont generator. It is possible to operate both the cross drum boiler and the high pressure La Mont generator under extremely varied loads and force them to ratings which, particularly in the case of the cross drum boiler, would result in stack temperatures so high as to be very uneconomical under ordinary circumstances, without any loss in efficiency as the increased stack temperature is promptly reduced by the low pressure La Mont generator which transforms the additional heat energy into low pressure steam. It is, therefore, possible to run an installation having relatively high peak loads with comparatively small generators and retain high economy at both high and low loads.

By a suitable proportioning of the series and series parallel water flow through the high pressure generator and the cross drum boiler, it is also possible to induce a circulation through the tubes 329 which is sufficiently rapid to overcome any danger of steam locking in these tubes with consequent danger of burnouts, even when the boiler is forced to a rating which under ordinary circumstances would be dangerously high. At the same time, the enhanced circulation presents many other advantages, such as increasing the steaming capacity of the water tube boiler very markedly, and at the same time reducing the tendency to scale in the generating tubes owing to the speed of flow through the tubes which results in a very marked scouring action and very largely prevents settling and deposition of scale forming ingredients. The whole installation is very flexible and can efficiently and reliably take care of loads varying through an extraordinarily wide range and high efficiency is preserved at all times.

The drawings, illustrating a few of the possible modifications of my invention, have been kept entirely diagrammatic and many of the accessories and incidental structural features which do not form any part of the present invention have not been specifically numbered and described and in some cases have not been illustrated. Thus, for example, no special description has been given of the conventional firing means such as grates, oil burners and the like which have been shown in conventionalized form in some of the figures. In a similar manner, safety valves or other boiler accessories have been omitted

in many cases or have been illustrated without specific description, but it should be understood that all such necessary or desirable structural features and accessories will be used in applying the principles of the present invention to any particular installation.

In most of the figures one of the generators has been shown as of the La Mont film tube type and the numerous advantages of high steaming capacity and rapid circulation which are inherent in this type of generator make it peculiarly fitted for use in combination with other generators in installations embodying the principles of the present invention. It should be understood, however, that the advantages which result from the positive circulation of the film tube generators and which aid in enhancing the circulation efficiency of the other generators associated therewith are not necessarily limited to a positively circulated generator of the film tube type and are also possessed by generators of somewhat similar construction which are designed to run with full or partially full tubes. It should be understood, therefore, that in all of the illustrations where La Mont film tube generators have been shown positively circulated generators operating with full or partially full tubes may be substituted and the advantages inherent in positive circulation and in the design of long tubes with small cross section will be retained, whereas, of course, the heat transfer advantages of the film tube will be lacking. In many installations, however, such full tube or partially full tube positively circulated generators may be very advantageous and they can be used in any of the modifications of the present invention, where the higher heat transfer capacity of the film tube is not an essential or may not be desired.

In the claims, the expression "pressure transformer" has been used in the same sense in which it has been used in the specification; that is to say, to cover any device which produces a change in pressure of a fluid flowing through it and the expression includes both pressure transformers which increase the pressure such as, for example, pumps, and pressure transformers which decrease the pressure which may consist in throttle valves, turbines, restricted tubes, injector orifices and the like.

It should be noticed that in some of the modifications, for example, that shown in Fig. 10, an intermediate pressure generator acts as a pressure transformer for the water which is circulated from the high pressure generator to the low pressure generator or vice versa. In the claims, therefore, it should be understood that the expression "pressure transformer" is not limited to a single device such as a pump or a reducing valve, but includes also one or more interme-

diate generators or other devices in combination with pumps or reducing valves. In general, therefore, any device or series of devices which bring about a change in pressure of the water or other fluid flowing through them are to be considered as pressure transformers and are included under this expression in the claims.

The expression "boiler of the water circulating type" or "generator of the water circulating type" is used in the claims to differentiate water tube, fire tube, film tube and similar generators in which water is actually circulated, from generators of the flash or semi-flash type in which there is no complete circuit of water in the liquid phase.

I claim:

1. Apparatus for the generation of steam, comprising the combination with a steam generator of the water circulating type of at least one set of auxiliary steam generating tubes, means for generating steam in the auxiliary steam generating tubes at a pressure different from that of the steam generator, said means including a connection through a suitable pressure transformer between the steam generator and the auxiliary generating tubes, and means for causing a part at least of the water from one of the steam generators to flow through said connection into the circulation of the other generator so as to be effective for causing circulation in said other generator.

2. An apparatus according to claim 1 in which at least one of the generators is heated by the same heating gas which flows in series through another generator and in which at least the auxiliary generating tubes are supplied with water in quantity less than sufficient to fill the tubes and are located in a zone of lower heat of the series gas flow.

3. Apparatus according to claim 1, in which the water circulating generator and the auxiliary steam generator are so arranged that the heating gases flow in series through the generators, and in which the generator operating at the lower pressure is provided with tubes to which water is supplied in quantity less than sufficient to fill them and is situated in a zone of lower heat.

4. An apparatus for generating vapors at different pressures including at least two generators, said generators comprising tubes to which vapor generating heat is applied and to which the liquid to be evaporated is supplied in quantity greater than the evaporating capacity of the tubes, a pressure transformer, means for passing all of the unevaporated water from one of the generators through said transformer into the other generator operating at a different pressure, and means for returning the unevaporated water from the last generator to the first generator.

5. An apparatus according to claim 4, in which the lower pressure generator is pro-

vided with injection orifices at the inlet to each tube thereof for insuring the delivery of the water in said excess quantity to each tube which serve as pressure transformers, and in which a pump is provided for circulating the water from the lowest pressure generator to the highest pressure generator. 70

6. Apparatus according to claim 1 in which the pressure transformer is controlled by means responsive to variations in the volume of the water in the water circulation in one of the generators. 75

7. Apparatus for the generation of steam comprising a steam generator of the water circulating type, at least one set of auxiliary steam generating tubes for generating steam at a pressure different from that of the steam generator, a conduit between the generator and the set of tubes through which water may flow from the one to the other, means for causing a part at least of the water of the generator to flow through the auxiliary steam generating tubes, and means for so controlling the flow of water through the conduit that the generator continues to generate 80 steam at a pressure which is different from that of the auxiliary tubes. 90

8. Apparatus for the generation of steam at two different pressures comprising two separate steam generating units, a connection to the low pressure generator from the water space of the high pressure generator, means in said connection responsive to the variation in the quantity of water in said low pressure generator for controlling the passage of water from the high pressure generator to the low pressure generator to maintain the quantity of water therein. 95 100

9. Apparatus for generating vapors at different pressures comprising a plurality of 105 sets of vapor generating tubes, means for applying heat thereto and for generating vapor in at least one set at a different pressure from the others, means utilizing the pressure of a set at higher pressure to deliver liquid to a set at lower pressure and 110 means for causing said delivered liquid to generate a circulation of the liquid in the set at lower pressure.

10. Apparatus according to claim 9 in 115 which at least one generator is provided with means for producing a positive circulation of liquid therein, said means also being used for return of the liquid to a generator at higher pressure. 120

11. Steam generating apparatus comprising a steam generator having tubes arranged for circulation of water therethrough, means for applying heat for the generation of steam under pressure in said generator, a second generator having tubes to which water is positively delivered in quantity in excess of the evaporation therein, means for generating steam in said second generator at a pressure different from that in the first 125 130

generator, a connection between the generators for the flow of water from one generator to the other, means associated with said connection whereby while maintaining the difference in pressure the excess water discharged from the tubes of the second generator is caused to flow into the circulation of the first generator.

12. Steam generating apparatus comprising a steam generator having tubes arranged for circulation of water therethrough, means for applying heat for the generation of steam under pressure in said generator, a second generator having tubes to which water is positively delivered in quantity in excess of the evaporation therein, means for generating steam in said second generator at a pressure different from that in the first generator, a connection between the generators for the flow of water from one generator to the other, means associated with said connection whereby while maintaining the difference in pressure the excess water discharged from the tubes of the second generator is caused to flow into the tubes of the first generator so as to circulate with the water circulating therein.

13. Apparatus for generating steam at different pressures comprising a set of generating tubes arranged to operate at a selected pressure, a set of generating tubes arranged to operate at a lower pressure, means for delivering water to each set of tubes at one end thereof in quantity in excess of the evaporation therein, connections through which the excess water from one set of tubes is delivered to the receiving end of the other set of tubes, pressure transformers in said connection for controlling the flow of water from each set to the other and means for generating steam in each set at their respective pressures.

14. Apparatus for the generation of vapor at two different pressures comprising two vapor generators, means for generating vapor in each generator at the required pressure, means for causing liquid to flow from one generator to the other while maintaining the operation of the generators at their respective pressures, and means for causing said flow of liquid to effect a circulation of the liquid in said other generator.

15. Apparatus for the generation of steam at two different pressures comprising two separate steam generating units each having a water circulation therein, a connection to the low pressure generator from the water space of the high pressure generators, means in said connection effective to cause the pressure of the high pressure generator to deliver water to the low pressure generator to replace that removed by evaporation in said low pressure generator and maintain the circulation therein.

16. Apparatus for generating vapor of the

same fluid at two different pressures comprising two vapor generators each containing a portion of the fluid in liquid form from which the vapor is generated, means for generating vapor in each generator at the required pressure, means for causing a portion of the fluid from one of the generators to flow into the other generator while maintaining the difference in pressure in the generators, means for causing said flow of fluid to induce a circulation of the liquid in said other generator.

17. Apparatus for generating vapor of the same fluid at two different pressures comprising two vapor generators each containing a portion of the fluid in liquid form from which the vapor is generated, means for generating vapor in each generator at the required pressure, means for causing a portion of the fluid from one of the generators to flow into the other generator while maintaining the difference in pressure in the generators, means for causing said flow of fluid to induce the feeding of additional fluid to the system to replace that evaporated therein.

18. Steam generating apparatus comprising two steam generators of the water circulating type, means for generating steam therein at two different pressures, means including conduits connecting the generators and pumps connected to said conduits so that at least a portion of the water circulating in one generator may pass through at least a portion of the other generator and coincident with the circulation of said other generator.

19. Steam generators operating at different pressures and having tubes through which the water circulates, conduits connecting the generators, pumps in some of said conduits to cause the water to flow from the low pressure generators to high pressure generators and to circulate therethrough, and pressure reducing valves in other conduits from the high pressure generators to the low pressure generators arranged to cause the water to flow from the high pressure generators to the low pressure generators and to circulate therethrough under the pressure of the high pressure generators.

20. Steam generating apparatus according to claim 7 in which the auxiliary tubes are provided with orifices at the water inlet ends thereof supplying the tubes with water in quantity less than sufficient to fill the cross sectional area thereof but greater than can be evaporated in its passage therethrough, said orifices also acting as pressure transformers for controlling the flow between the generators so that the auxiliary tubes generate steam at a pressure lower than that of the steam generator.

21. A steam generating system comprising a steam generator heated by heating gases, an auxiliary generator which has a plurality of steam generating tubes and is also heated

by heating gases, conduits connecting said generator and said auxiliary tubes to form therewith a positively defined closed water circuit, a pressure generator for inducing flow of water in the circuit, means at the inlet ends of the tubes for so restricting the input of water to the respective tubes with relation to the amount of water supplied to the tubes as to properly apportion it to each tube and through which restricting means water is positively forced under the action of the pressure generator, and means for generating steam in the steam generator at a pressure which is different from that in the auxiliary tube generator.

Signed at New York, New York, this 10th day of June 1926.

WALTER DOUGLAS LA MONT.
